UNITED STATES PATENT OFFICE.

ALVAH L. PERKINS, OF NEEDHAM HEIGHTS, MASSACHUSETTS, ASSIGNOR TO THE WILLIAM CARTER COMPANY, OF NEEDHAM HEIGHTS, MASSACHUSETTS, A CORPORATION OF MASSACHUSETTS.

UNION-UNDERGARMENT.

1,276,407.

Specification of Letters Patent. Patented Aug. 20, 1918.

Application filed May 24, 1913. Serial No. 769,556.

To all whom it may concern:

Be it known that I, ALVAH L. PERKINS, a citizen of the United States, and a resident of Needham Heights, in the county of Norfolk and State of Massachusetts, have invented an Improvement in Union-Undergarments, of which the following description, in connection with the accompanying drawings, is a specification, like characters on the drawings representing like parts.

This invention relates to undergarments, and particularly to union undergarments intended for use by men.

In order that the principle of the invention may readily be understood, I have disclosed a single embodiment thereof in the accompanying drawings, wherein,

Figure 1 is a front elevation of a union undergarment embodying my invention;

Fig. 2 is a rear elevation thereof;

Fig. 3 is a vertical, longitudinal section upon the line 3—3 of Fig. 1, the upper part of the garment being broken away;

Fig. 4 is a transverse section upon the line 4—4 of Fig. 3;

Fig. 5 shows the right and left gussets inserted in the lower body portion of the garment;

Fig. 6 is a somewhat diagrammatic representation of the lower portion of one of the gussets and surrounding portions of the garment, and indicating the direction of the wales;

Fig. 7 is an outside, detail view at the crotch of the garment; and

Fig. 8 is a detail view, somewhat diagrammatic, of the inside of the garment at the crotch portion.

The garment of my invention, and of which I have represented one embodiment, is a union undergarment, completely covering the person both at the front and at the rear but permitting the ready opening thereof for toilet purposes.

In the several views of the drawing I have indicated a union undergarment, preferably knitted in order to obtain great elasticity, the wales throughout the body portion, the leg portions and the gussets extending longitudinally of the body, thereby securing great lateral elasticity. The garment may be knitted in any suitable manner, as for example upon a circular or flat knit-

ting machine, so as to produce the body portion 1, which is preferably open in front from the neck 2 down to the top of the crotch portion 3 as indicated at 4, suitable buttonholes and buttons 5 being provided as indicated. The leg portions, which are indicated at 6 and 7, are preferably integrally formed with the body portion and are provided with inside leg seams, one of which is indicated at 8 in Fig. 3.

In the ensuing description the terms "right" and "left" will be used in describing the portions of the garment with reference to the wearer and not the observer.

In order to provide the proper fullness across the hips or thighs, and in order also to provide a suitable opening at the back and a proper support or suspensory at the crotch, I have provided two gusset portions respectively indicated at 9 and 10 in Fig. 5. The gusset indicated at 9 is herein designated as the left gusset because the greater portion of its perimeter is seamed to the left leg of the garment, and conversely the right gusset 10 has the greater portion of its perimeter seamed to the right leg of the garment. The knitted wales in the gussets 9 and 10 extend lengthwise thereof and it will be observed that the lateral edges 11, 12 and 11', 12' of these gussets are cut upon curved lines which converge toward each other. Each gusset has a square upper end 13, 13', which are lapped past each other and seamed to the body of the garment at the rear, as indicated at 14 in Fig. 2. The edge 12 of the gusset 9 and the edge 12' of the gusset 10 constitute the free edges of the garment at the rear; and the edges 11, 11' of the said gussets, which as previously described are cut upon curved lines, are seamed to straight edges of the body portion of the garment, thus giving increased width across the hips and thighs of the wearer.

An important object of my invention is to provide a garment wherein the crotch portion constitutes a suspensory. In accomplishing this purpose I provide each gusset with two gores, numbered respectively 15, 16, and 15', 16'. The gore 15 of the left gusset 9 constitutes a thigh-widening gore and is attached along both its edges to the inside seam of the left leg, thus enlarging the diameter of the upper portion of the leg

- and the gore 16 of the said left gusset constitutes a suspensory-forming gore and is carried over and attached to the inside seam of the right leg just below the crotch, as indicated more clearly in Figs. 7 and 8. As indicated most clearly in Fig. 5, the said gore 16 is provided with a widened extremity 17, which is seamed along its extent as described, to the inside seam of the right leg.
- 10 The gore 15' of the right gusset 10 constitutes a thigh-widening gore and is seamed along both its edges to the inside seam of the right leg, thus enlarging the diameter of the upper portion of the leg, and the gore 15 16' constitutes a suspensory-forming gore and is carried across and seamed to the inside seam of the left leg at the upper portion thereof, just below the crotch. It will be observed that the gores 16, 16' of the 20 gussets 9 and 10 differ in shape, the gore 16 being broadened at its lower edge as indicated at 17. The portion of the gore 16' that is seamed to the inside seam of the left leg is that indicated at 17' in Fig. 5.
- 25 Inasmuch as the portions of the gores 16, 16' are carried across and secured to the opposite leg seam they are therefore superimposed the one upon the other, the gore 16 being outermost in this embodiment of the 30 invention.
- The purpose of carrying the gores 16, 16' past each other and securing them to the upper portions of the inside seams of the opposite legs is to provide a suspensory or 35 support for the organs, and the purpose of making that portion of the gore 16 that is secured to the right leg wider than the corresponding portion of the gore 16' that is secured to the left leg is to make an enlargement or pocket at the left to accommodate the organs, which are more customarily and naturally supported at the left side of the crotch than at the right. This feature of my 40 invention, however, is not limited to a garment wherein the pocket portion is at the left because the reverse construction may be found preferable. Both of the suspensory-forming gores are positioned wholly at one 45 and the same side of the axial line of the crotch. Their upper ends are superposed and secured to the upper edges of the legs wholly at one side of said axial crotch line. It will be observed, viewing particularly Fig. 5, that the free rear edge of each gusset 50 slopes downwardly markedly toward the opposite side of the garment thereby to provide increased width at the lower ends of said gussets. It will also be observed, viewing said figure, that the two gore extensions 55 of each gusset are of substantially equal width, and that the suspensory-forming gore of each gusset is of generally triangular form and has one edge extending at a marked incline to and merging into a thigh-widening gore. Such construction permits

the locating of both suspensory-forming gores wholly at one and the same side of the axial line of the crotch.

It will be observed that the front opening 4 extends down to the top of the crotch portion 3, and this constitutes the preferred form of my invention, inasmuch as the lower portion of such opening is intended for toilet purposes.

In use the gores 16, 16' of the gussets 9 and 10 conform and lie close to the crotch portion of the body, and do not extend upwardly into contact with the abdomen.

It will be observed that inasmuch as the wales of all the porions of the garment extend lengthwise of the garment, at all the seams the wales run in the same direction excepting where the gores 16, 16' of the gussets 9 and 10 are supported and secured to the opposite leg portions. At all points of the garment, however, great lateral elasticity is provided and especially across the thighs and at the crotch, so as to permit the body to be readily bent.

Owing to the marked fullness which is given to the garment across the hips and thighs, the garment even before use naturally assumes a pocket formation at the hip portions, as indicated most clearly in Figs. 3 and 4. In other words, the increased fullness across the hips and thighs appears in the unstretched, unworn garment and is not merely secured by the stretching of the garment in use as is customary in garments heretofore manufactured.

Owing to the fullness imparted to the garment there is no strain thereon lengthwise of the garment, and for the same reason the overlying portions of the garment at the rear always cover that portion of the body excepting where purposely separated.

Owing to the fact that the wales of all portions of the gussets extend longitudinally of the garment, the crotch and suspensory portions thereof are exceedingly elastic and thus support the organs perfectly and yet permit perfect freedom of movement of the body.

Having thus described one illustrative embodiment of my invention, I desire it to be understood that although specific terms are employed, they are used in a generic and descriptive sense and not for the purposes of limitation, the scope of the invention being set forth in the following claim.

Claim:

A union undergarment for males having a body with a permanently closed crotch and legs and two inserted gussets having suspensory extensions, each gusset extending up the back of the garment and having one upright edge thereof secured to the body of the garment in the back and one upright edge free therefrom, each gusset having a thigh-widening gore extending from its lower end

downward into the leg at that side of the body to which such gusset pertains, the edges of each of said thigh-widening gores being secured to the edges of the respective legs, each gusset also having an upwardly extending suspensory-forming gore, the apex of the outer suspensory-forming gore of the garment being positioned wholly at the opposite side of the axial line of the garment from the thigh-widening gore to which said suspensory-forming gore pertains, and the apex of the other or inner suspensory-forming gore being superposed against the outer suspensory forming gore

5
10

at said opposite side of the axial line of the 15 garment, whereby the superposed portions of said suspensory-forming gores are wholly at one side of said axial line of the garment, thereby providing a suspensory pocket at one side of said axial line.

20

In testimony whereof, I have signed my name to this specification, in the presence of two subscribing witnesses.
